DOUBLE ACTING RATCHET WRENCH

Filed June 5, 1926

UNITED STATES PATENT OFFICE.

KARL LANGKAMMERER, OF MUNICH, GERMANY, ASSIGNOR TO ROBEL & CO., OF MUNICH, GERMANY.

DOUBLE-ACTING RATCHET WRENCH.

Application filed June 5, 1926, Serial No. 113,985, and in Germany July 28, 1925.

This invention relates to improvements in double acting ratchet wrenches in which separate levers are arranged for oscillatory movement round a ratchet wheel so as to impart to the wheel a uniform and continuous rotation through the medium of pawls on the levers. This kind of wrench is used for tightening and loosening nuts on screw-bolts, and especially for tightening up the 10 nuts on railway fishplates.

The objects of my improvements are firstly to provide a double acting ratchet wrench in which the actuating levers may temporarily be coupled together to form in 15 effect one lever; and secondly to prevent undesirable side play or side thrusts at the gripping ends of the levers.

I attain these objects in a manner that will be understood by reference to the following 20 description and the accompanying drawing, whereon:—

Fig. 1 is a side view of one constructional form of spanner embodying the features of my invention; and

Fig. 2 is a front view of the wrench, partly in section.

Referring to the drawing, the wrench comprises two adjacent levers *a:a* turnable around a ratchet wheel *b*, which is provided 30 with a polygonal opening to accommodate the nut to be tightened. Outward lateral movement of the levers *a:a* is prevented by means of two adjusting nuts *c:c*. Pawls *d:d* engage, in the usual way, with the teeth 35 of the ratchet wheel *b* and are pressed inwardly by springs *e:e*, which tend to prevent the pawls disengaging the ratchet wheel.

Concentrically arranged with respect to 40 the axis of rotation of the levers are co-acting guide segments *f* and *g* which are fitted to the levers in order to prevent side play of the latter. At the handle end of one of the levers a clip *i* is turnable around a pin 45 *h* provided on said lever, a slot *k* being provided in the other lever to receive the clip.

The operation of the device is as follows:—

The opening in the ratchet wheel *b* is ar- 50 ranged over the nut, which has already been partly screwed on to its bolt. The clip *i* is then brought into the position shown in dotted lines in Fig. 2, that is, disengaged from the slot *k*, whereafter the operator grasps

the levers *a:a*, one with each hand, and 55 swings them backward and forward.

The pawls *d:d* thus impart a uniform and practically continuous rotary motion to the ratchet wheel *b*, and therefore also to the 60 nut.

Undesirably large side thrust at the gripping ends of the levers is prevented by means of the segmental guide *f:g* fitted at a convenient distance from the point of rotation and which, as plainly shown in Fig. 2, 65 comprises a male segment *f* on one lever *a* and a female segment *g* on the other lever. The portions *f* and *g* engaged slidably with each other.

After the nut has been screwed up as far 70 as possible by using the two levers *a* and *a* independently for this purpose, more force will be required to tighten it up fully. This is because of the fact that for the purpose of reducing the weight of the wrench to a minimum each half of the wrench, that is each lever, is made only sufficiently powerful to take half of the total force needed. Consequently, in order to fully tighten the nut, the clip *i*, which can be swung around the 75 pin *h*, is caused to drop or catch into the slot *k* when the two levers *a:a* are exactly opposite each other. By this means both levers are locked together as one, so that the total force required to fully tighten up 80 the nut to its final position can be applied, in spite of the fact that each of the levers has been designed to take only half of this force.

The reverse process takes place when loos- 85 ening a nut. After the nut, which is often rusted in or very firmly set, has been loosened by using the two levers locked together as one, the clip *i* is moved from engagement with the slot *k*, whereupon the levers *a:a* are 90 actuated independently in the manner previously stated.

While I have described a certain or par- 95 ticular embodiment of my invention, I de- 100 scribe it to be understood that modifications may be made and I therefore intend no limitations other than those imposed by the scope of the appended claims.

What I claim is:—

1. The combination in a double acting 105 ratchet wrench of a ratchet wheel, levers mounted for independent oscillatory movement around the ratchet wheel, means on the

- levers engaging the ratchet wheel to impart continuous rotation thereto upon the levers being oscillated, and segmental guiding means fitted to the levers at a distance from the point of rotation for limiting side thrusts at their gripping ends. 5. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts at their gripping ends, there being a slot in the handle end of one lever and a pivoted clip on the handle end of the other lever for engaging said slot whereby said levers can be locked together at will to form in effect one single lever of substantially increased strength. 45
2. A double acting ratchet wrench comprising, in combination, a ratchet wheel, levers mounted closely adjacent for independent oscillatory movement around the ratchet wheel, means on the levers engaging the ratchet wheel to impart continuous rotation thereto upon the levers being oscillated, means for limiting side thrusts at the gripping ends of the levers, and means whereby the levers can be coupled together at will to form in effect one single lever of substantially increased strength. 50
3. A double acting ratchet wrench comprising, in combination, a ratchet wheel with a polygonal opening, two levers mounted closely adjacent for independent oscillatory movements around the ratchet wheel, pawls on the levers engaging the ratchet wheel to impart continuous rotation thereto upon the levers being oscillated, and a pivoted clip on the handle end of one of said levers for engaging a slot in the other lever whereby the levers can be locked together at will to form in effect one single lever of substantially increased strength. 55
4. A double acting ratchet wrench comprising, in combination, a ratchet wheel with a polygonal opening, two levers mounted for independent oscillatory movement around the ratchet wheel, pawls on the levers engaging the ratchet wheel to impart continuous rotation thereto upon the levers being oscillated, and two interengaging guide segments on the levers at a distance from the turning point for preventing undesirable side thrusts at their gripping ends. 60
5. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts at their gripping ends, there being a slot in the handle end of one lever and a pivoted clip on the handle end of the other lever for engaging said slot whereby said levers can be locked together at will to form in effect one single lever of substantially increased strength. 65
6. A double acting ratchet wrench comprising a ratchet wheel with a polygonal opening to receive the nut to be tightened, two levers mounted closely adjacent for independent oscillatory movement around the ratchet wheel each of said levers being designed to take half the total force to be applied to the wrench, means for retaining the levers in position on said ratchet wheel, pawls pivotally mounted on the levers, springs constraining the pawls into engagement with the teeth of the ratchet wheel so that said wheel will be rotated by the oscillatory movements of the levers, a male segment on one of the levers, a co-acting female segment on the other lever for the purpose of preventing undesirable side thrusts, there being a slot in the handle end of one of the levers and a clip pivoted to the outer end of the other lever for engagement with said notch whereby said levers can be locked together as one when the total force is to be applied. 70
7. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 75
8. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 80
9. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 85
10. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 90
11. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 95
12. A double acting ratchet wrench comprising a ratchet wheel with a polygonal opening, two levers mounted closely adjacent for independent oscillatory movement around the ratchet wheel, pawls on the levers engaging the ratchet wheel to impart continuous rotation thereto upon the levers being oscillated, two interengaging guide segments on the levers for preventing undesirable side thrusts, there being a slot in the handle end of one of the levers and a clip pivoted to the outer end of the other lever for engagement with said notch whereby said levers can be locked together as one when the total force is to be applied. 100

In testimony whereof I affix my signature.

KARL LANGKAMMERER.
